ACETYLENE GENERATOR FEED VALVE
VIBRATOR

Maurice P. De Motte, Indianapolis, Ind., assignor,
by mesne assignments, to Union Carbide and
Carbon Corporation, a corporation of New
York

Application October 29, 1931, Serial No. 571,914

9 Claims. (Cl. 121—1)

The invention is a vibrator for agitating the feed valve in an acetylene generator of the carbide-to-water type.

One object of the invention is to provide a vibrator that will operate whenever gas is drawn from the generator. Another object is to provide a vibrator that will operate regardless of the amount of gas being drawn from the generator. Other objects are to provide a vibrator that is simple in construction, low in cost, reliable in operation, and free from trouble. Other aims, objects, and novel features will be apparent from the following specification and the accompanying illustrations in which:

Fig. 1 is a fragmentary vertical section of an acetylene generator showing my improved vibrator attached to the carbide feed valve thereof.

Fig. 2 is a vertical section of one form of my improved vibrator showing the vibrating element 20 in rest position with one valve open.

Fig. 3 is a view similar to Fig. 2 showing the position of the vibrating element during operation with the other valve open.

Fig. 4 is a vertical section of another form of my vibrator.

Fig. 5 is a sectional view taken along 5—5 of Fig. 3, and

Fig. 6 is a sectional view taken along line 6—6 of Fig. 4.

In a medium pressure generator of the type described, the carbide feed valve has two motions: a vertical motion in response to the pressure within the generator to start and stop the flow of carbide, and a rocking motion, in response to the movement of gas being drawn from the generator, to produce a uniform rate of flow when the valve is open. The means for opening and closing the carbide feed valve comprises a diaphragm responsive to gas pressure within the generator and the means for rocking the valve comprises a vibrator in the gas outlet of the generator.

One example of my vibrator is shown in Figs. 2 and 3. This vibrator comprises a casing 10 having an inlet 11 at one end thereof and an outlet 12 at the bottom thereof. For convenience in manufacture the casing 10 may be composed of two parts that are joined at 13 by means of interfitting threads.

The interior of the casing 10 is provided with a horizontal cylindrical guideway 14; a beveled seat 15 in axial alignment with and slightly larger than the guideway; and a cylinder 16 in axial alignment with the guideway and the beveled seat and somewhat larger than either. A gas passage extends through the guideway, the bevel-

eled seat, and the cylinder, between the inlet 11 and the outlet 12.

A vibrating mechanism within the casing 10 comprises a cylindrical guide 17 slidably mounted in the guideway 14 and provided with a segmental passage 18 therethrough smaller than either the inlet 11 or the outlet 12. Integral with the guide 17 is a poppet valve 19 adapted to cooperate with the beveled seat 15 to close the gas passage through the casing 10. Guide 17 and poppet valve 19 are provided with an axial opening in which a shaft 20 is loosely fitted. Upon the inner end of shaft 20 a piston 21 is rigidly mounted. This piston 21 is provided with a stem 22 that normally rests against the poppet valve 19 for the purpose of holding the valve and piston in a spaced relation. The outer end of shaft 20 is provided with a nut or abutment 23 and between this nut and guide 17 a valve spring 24 is held in partially compressed condition. This spring 24 tends to normally hold poppet valve 19 in contact with the stem 22 of the piston 21.

An adjusting screw 25 is threaded in one wall of casing 10 and the inner end of this screw is provided with an abutment 26. Between this abutment 26 and the piston 21, a recoil spring 27 is held. Attached to shaft 20 is another shaft or rod 28 that connects the vibrating mechanism with another part of the generator, such as the carbide feed valve or an arm carried thereby.

During the operation of this vibrator gas at a pressure of about 15 pounds per square inch enters inlet 11 and passes through passage 18 and poppet valve 19, which is normally open and relatively remote from its cooperating seat as shown in Fig. 2, and exerts a pressure against the piston 21 that moves it in the direction of gas flow. During this movement shaft 20 and valve spring 24 carry poppet valve 19 substantially the length of chamber 19a until it closes. After it closes, the inertia of piston 21 and the shaft 20, and the gas pressure in the chamber 29 between the valve 19 and the piston 21 cause the piston 21 to move out of the chamber 29 and beyond the end of the cylinder 16 as shown in Fig. 3. This allows the gas in the chamber 29 to escape. As soon as the pressure of the gas in chamber 29 has been relieved the recoil spring 27 and valve spring 24 move piston 21 in the opposite direction and close the cylinder 16. After the piston 21 has closed the cylinder stem 22 of the piston 21 strikes valve 19 and then the whole vibrating mechanism is moved by spring 27 and the impact of the piston 21 until poppet valve 19 opens. This opening allows gas to again pass through the poppet valve 55

and bear against the piston and repeat the cycle after the inertia of the vibrating mechanism has been overcome. Therefore, as long as gas is being drawn from the generator through casing 10 of 5 the vibrator, the vibrating mechanism therein will continue to reciprocate and transmit its movement to the carbide feed valve of the generator.

Another example of my vibrator is shown in 10 Fig. 4. This vibrator comprises a casing 30 having a gas inlet 31 at one end thereof and a gas outlet 32 at the under side thereof. The casing 30 may be formed in two parts, for convenience in manufacture, and joined by interfitting 15 threads. The interior of casing 30 is provided with a cylindrical horizontal guideway 33; a beveled seat 34 in axial alinement with and somewhat larger than the guideway; and a cylinder 35 in axial alinement with guideway 33 and beveled seat 34 and somewhat larger than either. 20

A vibrating mechanism within the casing 30 comprises a guide 36 in guideway 33 having a passage 37 therethrough of smaller area than the inlet 31. A poppet valve 38 is integral with 25 guide 36 and is adapted to cooperate with beveled seat 34. A piston 39 is likewise integral with guide 36 and is adapted to move in and out of cylinder 35. Valve 38 and piston 39 are spaced thereby forming chamber 29 therebetween.

A gas passage is provided in the casing 30 through guideway 33, beveled seat 34, chamber 29, and cylinder 35. A recoil spring 40 between slide valve 39 and an abutment 41 carried by 30 screw 42 threaded in one wall of casing 30 is adapted to move the vibrating mechanism against the pressure of gas flow to close valve 38 and move piston 39 into cylinder 35 thereby closing the gas passage through the vibrator.

During operation the valve 38 is normally 40 closed, the piston 39 is in the cylinder 35, and gas entering inlet 31 presses against the under side of poppet valve 38. When this pressure reaches a point where the force of spring 40 is 45 overcome, poppet valve 38 is opened, and this opening allows the gas to press against the under side of piston 39. As the piston is larger than the poppet valve 38, the gas pressure exerts greater force and tends to quickly move it to 50 open position. This opens the passage through casing 30 and allows gas to pass through the vibrator and reduce the pressure at the inlet. This pressure is reduced quickly and then spring 40 moves the vibrating mechanism against the 55 flow of gas to closed position, from which the cycle of movement is repeated. Therefore, during the time that gas is being drawn from the generator through the vibrator the vibrating mechanism continues to reciprocate and this 60 movement is transmitted to the carbide feed valve of the generator.

The vibrators shown in Figs. 2, 3 and 4 may be provided with other conventional features, such as packing 43, packing nut 44, and lock nut 45.

The means of attaching my improved vibrator to an acetylene generator is illustrated in Fig. 1, which shows a generator casing 46 having a carbide hopper 47, and a carbide feed valve 48 at the outlet thereof, carried by or joined to a supporting lever 49 by means of a pivot 50. Lever 49 is adapted to be operated by diaphragm 51 in response to variations in gas pressure within the generator to open and close valve 48 in a manner well known in the art.

The inlet of my improved vibrator 52 is con-

nected by suitable pipe fittings 53 to and forms part of the main gas delivery outlet 54 of casing 46. A rod or shaft 28 attached to the vibrating element of my vibrator extends through fittings 53, outlet 54, and casing 46, and is joined by 5 pivot 55 to arm 56 forming a part of valve 48. Therefore, when gas is being drawn from the generator, the movement of the vibrating mechanism is transmitted through rod 28 to arm 56, thereby causing valve 48 to rock or vibrate on its 10 pivot 50, and this movement causes carbide to feed past the valve 48 at a more uniform rate.

My improved vibrator may be positioned otherwise than here indicated and it may be connected in a different manner with a carbide feed 15 valve of a different type from that shown, and clearly it need not vibrate the feed valve in the manner shown by way of illustration. Also equivalent elements may be substituted for those shown and they may be arranged in a different manner 20 without departing from the spirit of the invention or the scope of the claims.

I claim:—

1. A gas-operated vibrator comprising a casing 25 having an inlet and an outlet for gas, a cylinder formed in said casing, a piston in said cylinder constructed and arranged to move out of said cylinder, and a recoil spring normally holding said piston in said cylinder, in combination with a poppet valve for closing the inlet to said cylinder, said poppet valve being movable with said piston, a guideway formed in said casing, and a guide in said guideway connected to said poppet valve.

2. A gas-operated vibrator comprising a cas- 35 ing having an inlet and an outlet for gas, a cylinder formed in said casing, a piston in said cylinder constructed and arranged to move out of said cylinder, and a recoil spring normally holding said piston in said cylinder, in combination 40 with a poppet valve for closing the inlet to said cylinder, said poppet valve being movable with said piston, a guideway formed in the inlet end of said casing, and a guide in said guideway connected to said poppet valve, said guide having 45 a segmental gas passage therethrough.

3. A gas-operated vibrator comprising a cas- 50 ing having an inlet and an outlet for gas, a cylinder formed in said casing, a piston, and a recoil spring normally holding said piston in said cylinder, in combination with a poppet valve for closing the inlet to said cylinder, said poppet valve being movable with said piston, a guideway adjacent and in continuation of the gas inlet 55 in said casing, and a guide in said guideway connected to said poppet valve, said guide having a segmental gas passage therethrough smaller than the gas inlet in said casing.

4. A gas-operated vibrator comprising a cas- 60 ing having an inlet and an outlet for gas, a cylinder formed in said casing, a piston, and a recoil spring normally holding said piston in said cylinder, in combination with a poppet valve for closing the inlet to said cylinder, said poppet valve being movable with said piston, a guideway 65 formed in said casing, a guide in said guideway connected to said poppet valve, and a vibrating rod supported by said guide and movable with said piston, said rod being connected with the mechanism to be vibrated.

5. A gas-operated vibrator comprising a cas- 70 ing having an inlet and an outlet for gas, cylinder formed in said casing, a piston in said cylinder constructed and arranged to move out of said cylinder, and a recoil spring normally 75

holding said piston in said cylinder, in combination with a poppet valve for closing the inlet to said cylinder, said poppet valve being movable with said piston and said piston being movable independently of said poppet valve, a guideway formed in said casing, and a guide in said guideway connected to said poppet valve.

6. A gas-operated vibrator comprising a casing having an inlet and an outlet for gas, a cylinder formed in said casing, a piston in said cylinder constructed and arranged to move out of said cylinder, and a recoil spring normally holding said piston in said cylinder, in combination with a poppet valve for closing the inlet to said cylinder, said poppet valve being movable with said piston and said piston being movable independently of said poppet valve, a guideway formed in said casing, a guide in said guideway connected to said poppet valve, said guide having a segmental gas passage there-

7. A gas-operated vibrator comprising a casing having an inlet and an outlet for gas, a cylinder formed in said casing, a piston, and a recoil spring normally holding said piston in said cylinder, in combination with a poppet valve for closing the inlet to said cylinder, said poppet valve being movable with said piston and said piston being movable independently of said poppet valve, a guideway adjacent and in continuation of the gas inlet in said casing, and a guide in said guideway unitary with said poppet valve,

said guide having a segmental gas passage therethrough smaller than the gas inlet in said casing.

8. A gas-operated vibrator comprising a casing having an inlet and an outlet for gas, a cylinder formed in said casing, a piston, and a recoil spring normally holding said piston in said cylinder, in combination with a poppet valve for closing the inlet to said cylinder, said poppet valve being movable with said piston and said piston being movable independently of said poppet valve, a guideway formed in said casing, a guide in said guideway unitary with said poppet valve, and a vibrating rod supported by said guide and movable with said piston, said rod being connected with the mechanism to be vibrated.

9. A gas-operated vibrator comprising a casing having an inlet and an outlet for gas, a cylinder formed in said casing, a piston, and a recoil spring normally holding said piston in said cylinder, in combination with a poppet valve for closing the inlet to said cylinder, said poppet valve being movable with said piston and said piston being movable independently of said poppet valve, a guideway formed in said casing, a guide in said guideway unitary with said poppet valve, and a vibrating rod supported by said guide extending loosely fitted through said guide and said poppet valve and tightly connected to said piston, said rod being connected with the mechanism to be vibrated.

MAURICE P. DE MOTTE.
